UNITED STATES PATENT OFFICE.

DAVID SMAILIE SMITH, OF VANCOUVER, BRITISH COLUMBIA, CANADA.

EXTENSION-TABLE.

1,237,966.

Specification of Letters Patent.

Patented Aug. 21, 1917.

Application filed August 16, 1916. Serial No. 115,267.

To all whom it may concern:

Be it known that I, DAVID SMAILIE SMITH, a subject of the King of Great Britain, and a resident of the city of Vancouver, in the 5 Province of British Columbia, Canada, have invented certain new and useful Improvements in Extension-Tables, of which the following is a specification.

My invention relates to improvements in 10 extension tables of the kind in which the extension portions or leaves are adapted to be carried beneath the end sections and to be raised to fill the space between the same when the table is extended, and the object 15 of my invention is to devise a table of this class which is efficient, very simple in construction, and capable of being manufactured and sold at a low cost.

I attain this object by the construction 20 illustrated in the accompanying drawings in which—

Figure 1 is a plan view of the table when closed, the top being broken away to show the extension portions.

25 Fig. 2 is a transverse section on the line *a—b* of Fig. 1.

Fig. 3 is a transverse section on the line *c—d* of Fig. 1, showing the extension portion raised prior to lowering into place between the extended end sections.

Fig. 4 is a view similar to Fig. 3, but showing the position of the extension portion when raised into place in the extended table.

35 Fig. 5 is a longitudinal elevation on the line *e—f* of Fig. 1.

Fig. 6 is a detail view, in perspective, showing the method of mounting the hinges.

Similar figures of reference indicate similar parts throughout the several views.

1 indicates the middle section of my table, which section is stationary and to which is secured the supporting leg 2, which is of any approved design. 3 and 4 indicate the 45 movable halves of the table top, which halves may be provided with supporting legs (not shown) of any desired form, although in a pedestal table, as illustrated, such legs are not required. The two halves of the table 50 top are adapted and arranged to be separated and closed by hand by the usual or any preferred arrangement of sliding bars, such as shown in Figs. 1 and 2, in which 5 and 6 are bars having one end secured to the table-half 3, 7 and 8 are bars having one 55 end secured to table-half 4, while 9 and 10 are bars interposed longitudinally between the bars 5 and 7 and 6 and 8 respectively and connected to them by sliding dovetailed joints 11. The bars 9 and 10 are not secured to either table-half, but to the stationary middle section 1, from which it will be seen that the two table-halves may be drawn apart, or pushed together, as may be desired.

Secured to the middle section 1 are guide 60 bars 12 and 13, between which guide bars is slidably mounted a flat member 14, which member rests on top of the middle section 1 and moves thereon when the table is being opened or closed. Secured on the top side 65 of the member 14 at each end thereof are crossbars 15 and 16, the bar 16 being extended, as shown in Fig. 1, so that its ends may be engaged during the opening and closing of the table by stops 17—18 and 19—20 70 secured to the sliding bars 5 and 6, as hereinafter described. Each crossbar 15 and 16 has secured on its inner face adjacent its lower edge the pieces 21 and 22 respectively having slots 23 in each end in which the 75 hinges 24 and 25 operate and they are also provided with blocks 26—27 and 28—29 respectively, which serve to act as guides for the hinges and prevent lateral movement of the extension portions when being raised into 80 place.

The extension portions or leaves are formed as shown more particularly in Fig. 2, that is, having an intermediate portion 30, to which extensions 31 and 32 are hingedly 85 connected by suitable hinges 33, so that the extensions may be folded under the intermediate portion, as shown in Figs. 1 and 2, or opened out to the full width of the table, as shown in Figs. 3 and 4. Secured to the 90 underside of the intermediate portion 30 are the hereinbefore mentioned hinges 24 and 25, as shown in Fig. 3, the free leaf of each hinge being disposed, as shown in Figs. 5 and 6, in the slots 23 of the pieces 95 21 and 22 hereinbefore mentioned, and vertically movable therein so that a floating hinge connection is formed between the leaves and the member 14. The portion 30 is not mounted on the hinges adjacent the 100 hinge joints, as is the usual method of mounting, but is disposed toward and supported on the outer ends of the hinges at a 105 distance from their joints, as shown in Fig. 3, this distance being such that the folded 110

leaf when swung upwardly will clear the top of the sliding bars of the table to allow of the extensions 31 and 32 being unfolded.

I may here state that the hinges 24 and 25 need not necessarily be disposed in the slots 23 so as to be vertically movable therein, as the hinges may be secured to the crossbars 15 and 16 as well as to the intermediate portion 30. The floating hinge connection, however, is the preferred construction. 34 indicates a distance piece secured to the underside of the intermediate portion 30 to maintain the extensions 31 and 32 in parallel position.

15 The normal position of the extension leaves is as shown in Figs. 1 and 2, that is to say, the extensions 31 and 32 are normally folded under the intermediate portion 30 while the hinges 24 and 25 are 20 slidably mounted in their respective slots 23. The extension leaves then rest freely on top of the flat member 14 and between the sliding bars 5 and 6, and it will be noticed that the leaves are not connected to 25 any part of the table. To now extend the table the table-halves are pulled apart in the usual manner until they are clear of the first extension portion which, it will be observed, is disposed centrally of the table as shown in Fig. 1. This portion is then 30 raised by hand on its hinges 24 and 25 after the manner shown in Figs. 5 and 3, and the extensions 31 and 32 opened out the full width as shown in Fig. 3, whereupon the 35 extended leaf is allowed to drop to be supported on the sliding bars of the table and level with the extended table-halves 3 and 4, which may then be closed upon the extension leaf. Should further extension, 40 however, be desired, the table-halves are pulled apart until the second extension leaf is brought directly under the space formed by the further extending of the table, this extension leaf being carried into position 45 by means of the stops 19 and 20 which engage the crossbar 16 during the further extension of the table and move the flat member 14 and transverse bars 15 and 16 longitudinally so that the second extension portion 50 is carried into position for raising into place, which is accomplished in the manner already described with reference to the first extension portion.

To close the table, the extension leaves 55 are swung upwardly on their hinges 24 and 25 and their extensions 31 and 32 are folded under their intermediate portions 30, the folded leaves being then dropped to rest on the flat member 14, all as shown in Figs. 2 60 and 5. The table-halves 3 and 4 are then closed on one another, during which closing movement the folded extension leaves are carried to their normal positions by means of the stops 17 and 18, which engage the 65 crossbar 16 at a suitable moment so that

the flat member 14 is carried to its normal position.

On referring to Fig. 4, it will be seen that, when the extension leaves are in the raised position their respective hinges 33 70 have one leaf resting on top of the sliding bars of the table so that, in order that the surface of the extended table top may be level at all points, it is necessary to insert washers 35, as shown in Figs. 2 and 3, equal 75 in thickness to the hinge leaves, between the table-halves 3 and 4 and their respective sliding bars 5-6 and 7-8 respectively. The edges of the several leaves and table-halves are provided with dowels and 80 corresponding recesses in the manner common to extension tables, or any other suitable means of engaging the leaves and table-halves together when extended and closed may be used.

85 What I claim as my invention is:

1. In an extension table, the combination with the end members of an extension table top and means for extensibly connecting the table top end members together, of an extension leaf normally supported beneath the end members when said members are closed together and having at each end hinged portions normally folded under the leaf, said leaf being disposed between the extensible connecting means and adapted to be raised so that the said hinged portions may be unfolded and rested on the said extensible connecting means.

2. In an extension table, the combination with the movable end sections of an extension table top, central stationary section, and means for extensibly connecting the end section together, of a member loosely mounted on said stationary section, and an extension leaf hingedly connected to said member and having at each end hinged portions normally folded upon the leaf and resting on said member, said leaf being normally disposed between the extensible connecting means and adapted to be raised clear of said member so that the hinged portions may be unfolded and rested on the said extensible connecting means.

3. In an extension table, the combination with the movable end sections of an extension table top, central stationary section, and means for extensibly connecting the end sections together, of a member mounted on said stationary section, and an extension leaf having a floating hinge connection with said member and having at each end hinged portions normally folded upon the leaf and resting on said member, said leaf being normally disposed between the extensible connecting means and adapted to be raised clear of said member so that the hinged portions may be unfolded and rested on the said extensible connecting means.

4. In an extension table, the combination

with the movable end sections of an extension table top, central stationary section, and means for extensibly connecting the end sections together, of a member mounted on said stationary section longitudinally of the table and having a cross bar at one end, an extension leaf disposed between the extensible connecting means having at each end hinged portions normally folded upon the leaf and resting on the said member, and hinges secured to said leaf having their free ends vertically slidable on said crossbar.

5. In an extension table, the combination with the movable end sections of an extension table top, central stationary section, and means for extensibly connecting the end sections together, of a member mounted on said stationary section for longitudinal movement thereon, a pair of vertically adjustable extension leaves disposed side by side between the extensible connecting means, each leaf having a floating hinge connection with the said member and having hinged portions at each end normally folded upon the leaf and resting on the said member, and means for moving the said member longitudinally during extension of the table so as to carry the second extension leaf into position for vertical adjustment after the first leaf has been vertically adjusted.

6. In an extension table, the combination with the movable end sections of an extension table top, central stationary section, and means for extensibly connecting the end sections together, of a member mounted on said stationary section for longitudinal

movement thereon, a pair of vertically adjustable extension leaves disposed side by side between the extensible connecting means, each leaf having a floating hinge connection with the said member and having hinged portions at each end normally folded upon the leaf and resting on the said member, means for moving the said member longitudinally during extension of the table so as to carry the second extension leaf into position for vertical adjustment after the first leaf has been vertically adjusted, and means adapted to return said member to its normal position during closing of the table after the extension leaves have been lowered.

7. In an extension table, the combination with the movable end sections of an extension table top, central stationary section, and means for extensibly connecting the end sections together, of a member loosely mounted on said stationary section longitudinally of the table and having a cross bar at one end, an extension leaf disposed between the extensible connecting means having at each end hinged portions normally folded under the leaf and resting on said member, and hinges secured to said leaf and arranged to carry it clear of the extensible connecting means when swung upwardly, the free ends of said hinges being loosely mounted on and vertically slidable in said crossbar.

Dated at Vancouver, B. C., this 31st day of July, 1916.

DAVID SMAILIE SMITH.
